US00D510885S

(12) **United States Design Patent** (10) Patent No.: **US D510,885 S**
 Dueker et al. (45) Date of Patent: **** Oct. 25, 2005**

(54) **ILLUMINATED SIGNALING DEVICE**

(75) Inventors: **Kenneth S. Dueker**, Atherton, CA (US); **Paul M. Hagelin**, Saratoga, CA (US); **Troy J. Edwards**, Campbell, CA (US); **Russell E. Tavernetti**, San Carlos, CA (US)

(73) Assignee: **PowerFire Corporation**, Menlo Park, CA (US)

(**) Term: **14 Years**

(21) Appl. No.: **29/190,130**

(22) Filed: **Sep. 15, 2003**

(51) LOC (8) Cl. **10-05**

(52) U.S. Cl. **D10/114**

(57) **CLAIM**

The ornamental design for an illuminated signaling device, as shown.

DESCRIPTION

FIG. 1 is a front perspective view of the illuminated signaling device showing our new design.

FIG. 2 is a top plan view of FIG. 1.

FIG. 3 is a bottom plan view of FIG. 1.

FIG. 4 is a front elevation view of FIG. 1.

FIG. 5 is a back view of FIG. 1.

FIG. 6 is a right view of FIG. 1; and,

FIG. 7 is a left view of FIG. 1.
